DRESSING TABLE FOR INFANT'S BATH
STANDWilliam C. Baxter, Rochester, N. Y., assignor to
Trimble Nurseryland Furniture, Inc., Roch-
ester, N. Y., a corporation of New York

Application January 23, 1939, Serial No. 252,335

2 Claims. (Cl. 311—79)

This invention relates to a dressing table for an infant's folding bath stand, with more particular reference to the type of apparatus that includes a cross-legged or camp-stool type of stand with a tub supported thereby, and a dressing table positionable on the stand above the tub or movable to an inoperative upright position behind the tub, and it has for its object to provide a dressing table that is susceptible of such conventional positioning over or behind a tub, and which is disconnected from the folding stand and may be used on any table or flat surface independently of the folding stand.

Another object of the invention is to provide a dressing table that can be moved from a horizontal position on a folding stand above a tub to an inoperative upright position behind the tub where it can be supported conveniently on the back rail of the folding stand, while also being entirely removable from the stand for independent use.

A further purpose of the invention is to provide a dressing table of the character mentioned, with legs adapted to support the table spaced above any flat surface, and also adapted to support the table on a top rail of a folding stand and to permit its being moved readily from its normal operative position over the tub to inoperative vertical position supported on the rear top rail.

To these and other ends, the invention consists in the construction and arrangement of parts that will appear clearly from the following description when read in conjunction with the accompanying drawings, the novel features being pointed out in the claims following the specification.

In the drawings:

Fig. 1 is a front elevation of a conventional type of folding stand and tub, showing a dressing table embodying the invention supported on the stand over the tub;

Fig. 2 is an end elevation of the same;

Fig. 3 is an enlarged view showing the folding stand and tub in section and broken away, with the dressing table supported in upright inoperative position on the back rail of the stand;

Fig. 4 is an end elevation showing the stand collapsed and with the dressing table supported thereon;

Fig. 5 is a bottom plan view of the dressing table, partially broken away;

Fig. 6 is a detail sectional view of the dressing table showing one of the supporting legs, and

Fig. 7 is a side elevation showing the dressing

table resting on a flat surface for use independently of the folding frame.

Referring more particularly to the drawings in which like reference numerals refer to the same parts throughout the several views, 1 and 2 designate legs of the folding leg frames pivotally connected at 3. The legs 1 are connected together at the top by the cross-rail 4, while the legs 2 are connected by the cross-rail 5, and between the cross-rails 4 and 5 is suspended a tub 6 of rubber or other suitable fabric, although it will be understood that the invention forming the subject matter of this application is equally applicable to a structure in which a porcelain or other tub is supported between leg frames of a folding stand.

7 designates the usual type of screen guard that is pivotally supported at the upper ends of the legs 1 and foldable between the leg frames when the structure is collapsed, as shown in Fig. 4. Heretofore in devices of this character, the general practice has been to mount a dressing table on the folding stand in such a way that it may be moved by sliding or swinging motions from a horizontal position over the tub and stand to a vertical inoperative position at the rear thereof, and this invention contemplates the provision of a dressing table that can be similarly supported on the stand above the tub or at the rear thereof, and can be entirely removed from the stand and used on a separate support, or flat surface, when it is desired to rest an infant thereon.

In order to accomplish this, the dressing table, which includes a canvas supporting frame consisting of a front piece 8, back piece 9 and end pieces 10 suitably joined at the corners, is provided with legs 11 secured in the back piece 9 at points in proximity to the rear corners of the frame, and legs 12 secured in the end pieces 10 at points in proximity to the front corners of the frame. The legs are so arranged that the distance between them from front to rear is such that when the stand is in operative or unfolded position, the legs 11 and 12 just clear the cross-rails 4 and 5 and occupy positions slightly rearwardly of the back rail 4 and slightly forwardly of the front rail 5, as shown in Fig. 2.

This arrangement serves to hold the dressing table on the folding leg frame somewhat firmly so as to prevent sliding or wobbling when in use. The legs 11 and 12 are located on the back piece 9 and end pieces 10, slightly removed from the corners, as shown in Fig. 5, in order to avoid the necessity of placing the legs at the joints between

the end pieces and front and rear pieces of the frame. 13 designates the canvas or other covering that is secured over the frame in any suitable way.

5 The legs 11 and 12 are of uniform length and each is preferably provided with a rubber tip 14 that is cemented or otherwise attached to the leg and includes an enlarged portion 15 at its outer end. The legs are of such length that they will 10 support the dressing table on the back rail 4 of the stand, as shown in Fig. 3, the enlarged portions 15 at the ends of the rubber tips 14 acting while at the same time permitting it to be readily 15 lifted and brought to its horizontal operative position, or to be removed entirely from the stand.

With this arrangement, the table can be easily 20 lifted and moved from the horizontal position shown in Fig. 2 to the upright inoperative position shown in Fig. 3 by the same motion that characterizes the pivotally connected table of the 25 art, and is retained on the cross-rail 4 against displacement from any slight pressure. The dressing table is also retained on the cross-rail 25 against the legs 1 of the leg frame when the stand is folded in the manner shown in Fig. 4, so that the entire structure can be carried or packed as a unit.

If desired, the table can be removed entirely 30 from the foldable stand and used on any flat surface or support in the manner shown in Fig. 7. The legs 11 and 12 at the corners of the table act to support it in spaced relation above the surface on which it is resting. In this fashion, the 35 table can be placed on a floor, bed, or other support, and used for resting an infant thereon, thus serving as a convenient dressing table either on the folding stand or separately therefrom.

While the invention has been described with 40 reference to the particular embodiment shown, it is not confined to the structural details herein disclosed, and this application is intended to cover such modifications or changes as may come within the scope of the following claims.

45 I claim:

1. The combination with a folding stand com-

prising pivotally connected leg frames including longitudinally extending front and back top rails and legs which extend vertically somewhat above the top rails, of a dressing table including a rigid canvas supporting frame removably positionable horizontally on said top rails or vertically on said back rail and consisting of front, rear, and end pieces, and legs of uniform length secured to said table frame in proximity to the corners thereof, said legs occupying positions slightly forwardly and rearwardly of the aforementioned front and back top rails respectively to limit forward and backward movement of the table frame when supported thereon horizontally, the upper ends of the legs of said leg frames acting to limit endwise movement of the table frame when the latter is positioned horizontally, said legs having enlarged portions at their outer ends which act to support the table frame in an inoperative upright position on one of said rails and to prevent its accidental removal therefrom.

2. The combination with a folding stand comprising pivotally connected leg frames including longitudinally extending front and back top rails and legs which extend vertically somewhat above the top rails, of a dressing table including a rigid canvas supporting frame removably positionable horizontally on said top rails or vertically on said back rail and consisting of front, rear, and end pieces, and legs of uniform length secured to said table frame in proximity to the corners thereof, said legs occupying positions slightly forwardly and rearwardly of the aforementioned front and back top rails respectively to limit forward and backward movement of the table frame when supported thereon horizontally, the upper ends of the legs of said leg frames acting to limit endwise movement of the table frame when the latter is positioned horizontally, said legs having rubber tips which include enlarged portions at their outer ends, said rubber tips and enlarged portions acting to support the table frame on one of said rails in an inoperative upright position and to prevent accidental removal thereof.

45 WILLIAM C. BAXTER.
